SUPPORTING CLAMP FOR TRACK
LUBRICATORSSidney E. Bates, Chicago, Ill., assignor, by mesne
assignments, to Poor & Company, a corpora-
tion of Delaware

Application June 15, 1936, Serial No. 85,348

8 Claims. (Cl. 184—3)

This invention relates to rail and wheel flange lubricators and particularly to improvements in devices for rigidly securing such lubricators to railroad rails.

5 The principal object of the present invention is to provide a simplified clamp structure which can be readily applied to rail base flanges of different widths and thicknesses and which, when applied to the rail, provide a rigid support for the 10 lubricant distributor and/or the wheel actuated mechanism of a rail and wheel flange lubricator.

A further and more specific object of the invention is to provide a supporting clamp comprising a jaw member formed to engage one 15 edge of a rail base and having a wedge engagement with one end of the bolt member, and a plurality of jaw members adapted to be interchangeably fitted on the other end of the bolt for engagement with the rail base flange at the other 20 side of the rail, whereby the supporting clamp structure can be readily varied to fit rail bases of different sizes and to provide suitable supports for different devices or mechanism of a track 25 lubricator.

25 Other objects and advantages will be readily apparent from the detailed description of the embodiments of the invention shown in the accompanying drawings.

In the drawings:

30 Fig. 1 is a side view in elevation of two lubricant distributing units clamped on a railroad rail by means of the improved clamp structures of the present invention.

35 Fig. 2 is a fragmentary side view of one form of pump operating mechanism for track lubricators secured in its operative position on the rail by means of clamp structures made in accordance with this invention.

40 Fig. 3 is a cross section taken on line 3—3 of Fig. 1 illustrating the position of the lubricant distributor and the pump operating mechanism on the rail and showing also the manner in which said lubricator elements are supported in their position on the rail by means of the improved 45 clamps.

45 Fig. 4 is a view in perspective of one of the jaw elements employed in one of the clamp structures.

50 Fig. 5 is a sectional view taken on line 5—5 of Fig. 1 illustrating one clamp construction.

55 Fig. 5a illustrates a clamp in which two of the parts are rigidly secured together.

Fig. 6 is a view in perspective of a bolt which forms part of the clamp shown in Fig. 5.

Figs. 7 and 8 are detail views of the jaw member shown at the right of Fig. 5, and

Fig. 9 is a view in perspective of the jaw member shown at the left of Fig. 3 for supporting and clamping the wheel actuated mechanism to the 5 rail.

For convenience in illustration, the improved supporting clamp structures of the present invention are illustrated in connection with the lubricant distributors and the wheel actuated 10 pump operating mechanism of a well known rail and wheel flange lubricator. The said clamp structures have been, therefore, constructed with reference to the particular requirements of the lubricating mechanism shown. It should be understood, however, that the clamp structures herein shown can be used as attaching devices for various other forms of track lubricators and in fact might be used in other situations where 15 similar conditions prevail.

20 In the drawings, two lubricant distributing units designated by reference numerals 10—10 are arranged in close relation to each other at one side of a railroad rail 11. Each unit comprises a wiping or lubricant supplying member 12 from which lubricant is discharged or otherwise caused to be applied to the rail head 13 and/or the wheel flanges 14 of passing car wheels. In order to properly position the distributing units relative to the top of the rail head 13 or 25 30 relative to the wheel flanges 14, and to also facilitate ready application to rails of different sizes, the said units are provided with adjusting screws 15 which extend through suitable lugs formed on the units and bear upon the top surfaces of the 35 rail base flange 16.

35 Lubricant is supplied to the above units by means of a suitable pump (not shown) adapted to be operated by wheel actuated mechanism 17. The said mechanism 17 may be of any suitable 40 construction. For the purpose of illustration it is shown herein as comprising a pivoted lever 18 mounted on a bar 19 to extend above the rail head so as to be depressed by passing wheels. By the downward movement of the lever it engages 45 an arm 20 of an oscillating shaft 21, the operations of which are transmitted to the said lubricant pump. The said wheel actuated mechanism, like the distributing units, is provided with adjusting screws 22—22 which seat on the top 50 surfaces of the rail base flange. Preferably the said wheel actuated mechanism is so positioned on the side of the rail opposite the adjacent ends 23—23 of the distributing units, that the said wheel actuating mechanism and the adjacent 55

ends of the distributors may be secured to the rail by means of the clamp structures designated 24-24. The outer ends of the distributing units are secured to the rail by means of clamp structures 25-25.

Each of the clamp structures designated by the numeral 25 comprises a jaw member 26 for engagement with one side of the rail base, a jaw 27 for engaging the other edge of the base, a connecting bolt 28 and nut 29, the latter of which engages one end of the bolt to force the various elements of the clamp into tight gripping engagement with the base portion of the rail. The jaw member 26 is in the form of a hollow bracket recessed at 30 to receive one edge of the rail base. The vertical dimensions of the recess 30 are somewhat greater than the thickness of the rail base flange so that the jaw member can be readily applied to base flanges of different thicknesses. The top portion 31 of the jaw preferably slopes inwardly toward the rail and provides a seat to which the lubricant distributor is attached by means of a bolt 32. Suitable shims 33-34 are preferably interposed between the distributor and the seat 31 to facilitate adjustment of the distributor to any desired vertical or angular positions on the rail. A number of shims may be used. Two shims are illustrated in the drawings, the shim 33 being of uniform thickness and the shim 34 being formed at one edge with an inturned portion which may be turned to any desired position on the seat 31 to vary the slope of the lubricant distributor relative to the rail. The bolt opening 35 in the jaw 26 is preferably elongated, as shown in Fig. 7, to permit lateral adjustment of the distributing unit relative to the rail. The side walls of the jaw member 26 (Figs. 7 and 8) are provided with inwardly projecting ribs which strengthen and rigidify the said walls and at the same time minimize the area of the frictional contact between the side walls of the jaw member and the side faces of the wedge bolt 28. The bottom wall of the jaw is rounded transversely of the jaw and inclines upwardly toward the center of the rail to provide an inclined wedge surface 37 which, in the assembled relation of the parts, engages a wedge portion 38 of the bolt 28. The top portion 39 of said bolt wedge bears flat against the bottom surface of the rail base when the clamp is in its applied position, whereby movement of the bolt in one direction transversely of the rail forces the wedge portion 38 thereof between the bottom surface of the rail base and the inclined surface 37 of the jaw member 26 and thereby forces the rail engaging jaw 40 of said jaw member into tight gripping engagement with the top surface of the rail base. The extremity of the wedge shaped end of the bolt is preferably inclined outwardly and downwardly relative to the rail, as indicated at 41, so that the bolt 32 can be readily applied or removed from its position between the side walls of the jaw member without disturbing the clamping bolt 28 or other elements of the clamp.

The jaw member 27 (Figs. 4 and 5) is adapted to fit slidably on the other end of the bolt 28 and is preferably provided with two rail base receiving recesses 42 and 43, which define jaw members adapted to grip the top and bottom surfaces of the rail base. The said recesses are of different dimensions so that one or the other of them will receive and tightly grip any one of the various sizes of rail base flanges now in general use. The bolt opening through said member 27

separates the portion of the member adapted to grip the bottom surface of the rail into two parts, designated 72a and 72b.

From the above description it will be apparent that a tightening movement of the nut 29 to draw the bolt 28 transversely of the rail will force the wedge portion 38 of the bolt into tight wedging position between the bottom surface of the rail base and the inclined surface 37 of the jaw member 26 and also force the jaw member 27 into tight gripping engagement with the rail base. The lubricant distributor 10 may be readily applied, removed or adjusted on the bracket portion of the jaw member 26 without disturbing any element of the clamp structure.

Referring now to the clamp structure designated generally by the reference numeral 24, in Figs. 1, 2 and 3: This combination clamp structure is quite similar to the clamp structure previously described in that the jaw 26 and the bolt 28 are the same as the corresponding elements used in the said clamp 25 previously described in connection with Fig. 5. The jaw member 44 at the other end of the bolt is somewhat different from the jaw member 27, in that it is provided with suitable means for attachment to the bar or frame structure 19 of the wheel actuated mechanism 17. The said jaw 44 comprises a shoe member formed with a U-shaped lower jaw portion 45 through which the threaded end portion 30 of the bolt 28 extends. The top portions 45a-45b of the lower jaw portion 45 bear against the bottom surface of the rail base at spaced locations lengthwise of the rail. The top jaw 46 is preferably flat and bears against the inclined top surface of the rail base. For this purpose the under-surface of the upper jaw is inclined at approximately the same angle as the top surface of the rail base. An arm portion 47 extends upwardly from the upper jaw 46 and is adapted to be clamped by suitable bolts 48 to the supporting bar 19 of the wheel actuated mechanism 17. In order to permit suitable adjustment of the wheel actuated mechanism the bolt receiving opening 49 in the arm 47 is elongated, as shown in Figs. 2 and 9. Suitable shims 50 may be interposed between the bar 19 and the arm 47 of the clamp jaw to facilitate proper spacing of the bar 19 and the elements supported thereon relative to the rail.

In Fig. 5a the jaw 26 and the bolt 28 are shown secured together by a suitable bolt or rivet 51 so that these members are maintained in fixed relation to each other. By this means of assembly the said clamp members may be secured together at the factory to fit the rail or to maintain a fixed clearance between the vertical edge 52 of the rail base and the vertical edge 53 of the clamp.

While the invention is illustrated in connection with one specific embodiment of rail and wheel flange lubricators and in connection with certain preferred clamp jaw constructions it will be readily apparent from the above description that various modifications of the clamp structures might be made without departure from the principles of the invention. It should be understood, therefore, that the present invention contemplates all changes in structure coming within the scope of the appended claims.

I claim:

1. A clamp device for securing rail and wheel flange lubricating mechanisms on a railroad rail comprising: a jaw member recessed to receive one edge of a rail base flange and having a portion

75

- for attachment to a part of said mechanism, a jaw member formed with portions for gripping the top and bottom surfaces of the base flange at the other side of the rail, and connecting means for forcing said jaws into tight gripping engagement with the rail comprising a bolt member formed with a tapered portion adapted to wedge between the rail base and one of said jaw members. 5
2. A clamp device for securing rail and wheel flange lubricating mechanisms to a railroad rail comprising: a jaw member recessed to receive one edge of a rail base flange and having a portion for attachment to a part of said mechanism, a jaw member recessed to provide portions for gripping the top and bottom surfaces of the rail base flange at the other side of the rail, and connecting means for forcing said jaws into tight gripping engagement with the rail base comprising a bolt extending across beneath the rail base 10 and formed at one end with a tapered portion adapted to wedge between the rail base and one of said jaw members. 15
3. A clamp device for securing rail and wheel flange lubricating mechanisms on a railroad rail comprising: a jaw member recessed to receive loosely therein one edge of a rail base flange so as to engage the upper and vertical surfaces thereof and having a portion for attachment to a part of said mechanism, a jaw member recessed to receive the edge portion of the rail base flange at the other side of the rail, and connecting means for forcing said jaws into tight gripping engagement with the rail base comprising a bolt extending across beneath the rail base and formed with a tapered portion adapted to wedge between the bottom surface of the rail base and said loose fitting jaw member to force this jaw member into tight gripping engagement with the top surface of the rail base flange engaged. 20
4. A clamp bracket for supporting a separable element on a railroad rail comprising: a jaw member adapted to engage the top and vertical surfaces of one base flange of a rail and having a portion for attachment to said separable element, a jaw member recessed to engage the top and bottom surfaces of the base flange at the other side of the rail, and means for connecting said jaw members and for forcing them into gripping engagement with said base comprising a bolt movable transversely of the rail and provided with a tapered portion adapted to wedge between the bottom surface of the rail base and the first mentioned jaw member. 25
5. A clamp bracket for supporting a separable element on a railroad rail comprising: a jaw member recessed to receive rail base flanges of different thicknesses and having a portion above the rail base for attachment to the element being supported, a jaw member at the other side of the rail having a plurality of recesses therein adapted to receive and grip the top and bottom 30
- surfaces of rail flanges of different sizes and means for connecting said jaw members and for forcing them into gripping engagement with said base comprising a bolt movable transversely of the rail and provided at one end with a tapered portion adapted to wedge between the bottom surface of the rail base and the first mentioned jaw member. 5
6. A clamp device for securing rail and wheel flange lubricating mechanism on a rail comprising: a hollow jaw member for engagement with one flange of a rail base and including a seat portion on which a part of said mechanism is supported, spaced side walls and a bottom surface, the latter of which inclines outwardly and downwardly transversely of the rail; a jaw member for engaging the top and bottom surfaces of the rail base flange at the other side of the rail; a wedge bolt extending through said jaw member and movable transversely of the rail to force the jaws 10 into tight gripping engagement with the rail base, one end of said bolt being adapted to wedge between the bottom of the rail base and the inclined bottom of the first mentioned jaw; and means for moving the bolt relative to the jaws 15 to force the jaws into clamping engagement with the rail base. 20
7. A clamp device for securing rail and wheel flange lubricating mechanism on a railroad rail comprising: a hollow jaw member for engagement with one flange of a rail base and including a seat portion on which a part of said mechanism is supported, spaced side walls formed with inwardly projecting rigidifying ribs and a downwardly and outwardly inclined bottom surface; a jaw member for engaging the other side of the rail base and having a plurality of jaws for accommodating rail bases of different thicknesses; a wedge bolt extending through said jaw members and movable transversely of the rail to force the jaws into tight gripping engagement with the rail base, one end of said bolt being adapted to wedge between the bottom of the rail base and the inclined bottom of the first mentioned jaw; and means for moving the said bolt relative to said jaws to force the said jaws into said rail clamping engagement. 30
8. A clamp device for securing rail and wheel flange lubricating mechanism on a railroad rail comprising: a hollow jaw member for engagement with the top and vertical edge surfaces of one flange of a rail base, a jaw member for engagement with the top and bottom surfaces of the other base flange and having an upwardly extending arm for adjustably supporting a part of said lubricator mechanism, and a wedge movable into wedging position between the bottom surface of the rail base and one of said jaw members and adapted to hold a jaw thereof in rail gripping position. 35
